UNITED STATES PATENT OFFICE.

WILLIAM HUNTER, OF DETROIT, MICHIGAN.

IMPROVEMENT IN FENCE-POSTS.

Specification forming part of Letters Patent No. **59,023**, dated October 23, 1866.

To all whom it may concern:

Be it known that I, WILLIAM HUNTER, of the city of Detroit, county of Wayne, and State of Michigan, have invented a new and Improved Fence-Post; and I do hereby declare that the following is a full and exact description thereof, reference being had to the accompanying drawings, and to the letters of reference marked thereon.

The nature of my invention consists in affixing certain flanges to the post in such a manner that when the same is driven into the earth it will remain fixed and immovable in an upright position without oscillation; and I do hereby declare that the following is a full, clear, and exact description of the construction and operation of the same, reference being had to the annexed drawings, making a part of this specification, in which—

Figure 1 shows a perspective view of said fence-post. A A represent the body of the post, composed of iron or other suitable material. B B B B represent the certain flanges, eight in number, projecting at right angles from said post, and so formed as to easily cut their way into the earth when driven. The post is sharp at the lower end, as shown at C.

Fig. 2 represents a section of an iron fence attached to the posts. A A represent two of the posts driven into the earth, which is tinted green. B B represent the said flanges.

Fig. 3 represents a perspective end view of said posts. A shows the sharpened body of said post, and B B B B the flanges.

Said post may be made of iron or of any suitable material, and the fence attached to the same may be made of iron, wood, or any material, of pattern or design as utility or taste may dictate.

What I claim as my invention, and desire to secure by Letters Patent, is—

1. The combination of flanges, such as above described, with a pointed fence-post, in the manner above described, for the purpose of making said post when driven into the earth firm and immovable, and incapable of oscillation, or any other arrangement of flanges so attached which will secure substantially the same effect.

2. The application of such flanges and the arrangement thereof to any article of use designed to be fixed in the earth, whether for fence-posts, lamp-posts, awning-posts, or any other article which, by substantially the same means, can be firmly fixed or driven into the earth.

WILLIAM HUNTER.
